UNITED STATES PATENT OFFICE.

JOHN WALDHEIM, OF ELIZABETH, NEW JERSEY, ASSIGNOR TO UNDERWOOD ELLIOTT FISHER COMPANY, OF NEW YORK, N. Y., A CORPORATION OF DELAWARE.

TYPEWRITER DESK.

Application filed October 18, 1924. Serial No. 744,319.

This invention relates to improvements in desks, having mechanism for locating a typewriting machine in typing or non-typing position.

- 5 In my application No. 741,348, filed October 3, 1924 (now Patent No. 1,656,714, dated January 17, 1928), a desk is shown for use with typewriting machines equipped with a sound-deadening cabinet.
- 10 In the present invention, a typewriter desk is illustrated in which provision is made to manually bring the typewriter into typing position, in a convenient location in front of the desk from a position in the 15 rear of the desk where the typewriter is normally kept out of the way.

In order to bring the typewriter into typing position means are provided in said application to sink the front section of the 20 desk-top simultaneously with the forward advancing of the typewriter-carrying section in the rear of the desk, so that, when the rear section reaches the typing position, the front section will have been lowered enough to 25 clear the typewriter-carrying section.

The strip, separating the two table sections in said application, is removed or swung on a suitable hinge out of the way and at the same time, due to specially provided linkage, a vertically-placed strip in 30 front of the desk, which supports the front section, is also removed so as to leave the two front and rear table sections free from each other and free to be moved in relation 35 to the desk.

When the strips locking said two sections have been removed, the front section of the table is forced downwardly and by means of suitable linkage the rear table carrying the 40 typewriter is swung forwardly and downwardly to place the typewriter in a convenient typing position.

Among the new features of this invention are, a new linkage designed to concomitantly 45 operate the two table sections, a supporting strip under the front section to effectively take the downward thrust of said front section, and means for automatically withdrawing said supporting strip from under 50 said front section simultaneously with the operation of the ordinary locking strip between the two table sections.

Other features and advantages will hereinafter appear.

60 In the accompanying drawings,

Figure 1 is a vertical sectional view on line 1—1 of Figure 4, showing the typewriter in normal or ineffective position.

Figure 2 is also a vertical sectional view on line 1—1 of Figure 4, but showing the typewriter in accessible or typing position.

Figure 3 is a horizontal vertical view on the line 3—3 of Figure 4.

Figure 4 is a front elevation, partly in section and broken away, showing the typewriter in normal or ineffective position.

Figure 5 is a front elevation, showing the typewriter in typing position.

In order to bring the typewriter into typing position, as shown in Figure 2, from the normal or standing position shown in Figure 1, it will be first necessary to unlock the front and rear sections of the table by removing a locking strip 12 between them, and also to remove a supporting strip 15 which normally takes the downward thrust of the front section 10 of the table and is mounted on a hinge 16. The locking strip 12 is swung on a hinge 14 and is folded flat over the front section 10, and, while swinging it, a forwardly extending arm 19 and a pin 18, operatively connected to a link 17, will also be swung to draw on the latter, which in turn will force the supporting strip or panel 15 to rock on the hinge 16 and to leave an opening under the front section 10, permitting the latter to sink when force is applied upon it, and to simultaneously clear the rear section 11, so that it may be moved forward.

Under the front section 10 there are mounted, in each side of the desk, two downwardly extending brackets 20 and 21, both fastened to the front section 10 by means of a frame 22. The forward bracket 20 is operatively connected to a T-shaped plate or guide-link 23 by means of a pin 24, said plate 23 being mounted on a fulcrum stud 25 fast upon a plate 56 which forms an integral part of the desk. There is provided another T-shaped plate or guide-link 27 similar to plate 23, and also fulcrumed at 26 upon the plate 56, and supporting at its forward end, by means of a pin 28, the bracket 21 which forms an integral part of the table front section 10. The two plates 23 and 27 are operatively connected at their lower ends by means of a link 29 and the two pins 30 and 31.

In order that the rear portion of the front

section 10, which carries upon it the locking strip 12, may be sunk lower than the forward portion, the pivot 26, upon which the plate 27 is swung, is placed lower than the pivot 25, which carries the plate 23, and, by reducing the distance between the fulcrum 26 and the link connection 30 as compared with the distance between the fulcrum 25 and link connection 31, while keeping constant the leverage supporting the front section 10 of the table, the rate of downward travel will be increased on the plate 27 in relation to the plate 23, thereby clearing the space occupied by the locking strip 12, so that it will not interfere with the rear section 11 when the same is moved forward to place the typewriter in typing position as shown in Figure 2.

The rear section carrying the typewriter is mounted on suitable linkage for the purpose of supporting the weight of the machine while it is being moved from ineffective to effective position, and, to this end, the rear section 11 is provided with two downwardly-extending brackets 42 and 43 operatively connected to two downwardly-extending levers or links 32 and 33, respectively fulcrumed at 34 and 35 upon two brackets 36 and 37 mounted upon the desk sides 51 by means of fasteners 38.

The front section 10 of the desk top is operated concomitantly with the rear section 11 by means of a link 39 operatively connected at the uppermost end to the plate 23 at 41, and at the lower end to a downwardly-extending arm 57, which forms an integral part of lever 33, by means of a pin 40. The plate 23 fulcrumed at 25 when moving downward will force the link 39 in the same direction, and actuating on the extending arm 57, by means of the pin 40, will cause the lever 33 to move forward.

When the typewriter is placed in a typing position, as shown in Figure 2, the space normally enclosed by the rear section 11 will be left open, and to close the opening, there is provided a shelf 44, arranged at the rear of the desk directly beneath the typewriter-carrying section 11 and mounted at the ends upon support-plates 45, so that it will serve as a closure when the rear section 11 is moved forward, in which position the rear section 11 is substantially in the same plane as the shelf 44 and forms a continuation of the section 11.

Stop-pins 46 and 47 are designed to limit the travel of the movable top sections. The pin 46 interposes the lever 33, thus preventing the rear section from being forced too far back, while the pin 47 interposes the lever 32 and limits the forward travel of said rear section, so as to hold the same in its lowered or typing position.

A counterbalancing spring 48 is oper-

atively connected to the linkage by means of a fastener 49 upon lever 32, and is at the other end fastened to the sides of the desk at 58, being placed in relation to the link 32 and to the fast end of the spring 48, so that its tension will gradually increase as the link is moved forward, the spring being stretched the most when the most power is needed to counterbalance the weight of the typewriter. This spring 48 is consequently necessary to restore the typewriter to ineffective position with the least effort on the part of the operative.

It will be noted that the mechanism heretofore described is duplicated in the desk, the same mechanism being partly mounted on the two sides of the desk 51 and partly on the two supporting plates 56 fast upon the rear panel 50.

The desk is shown in the form of a flat-top desk and comprises the back panel 50 with re-enforcements fastened to the sides of the desk 51. The front part of the desk is provided with a framework to support the slidably-mounted drawers 52 in guides 53, and the top of the desk, which is formed by the manually-operable front and rear sections, extends the full width of the desk except for the two end bars 54 at the opposite sides of the desk in line with the contiguous edges of the top sections.

The noiseless cabinet 60, which encloses a typewriter 59, extends substantially the full width of the desk and includes a plurality of built-in drawers 55 and other features disclosed in my said application, No. 741,348.

From the foregoing, it will be understood that there is provided a desk having a top which is divided into two main sections, namely, a forward section 10 and a rear section 11, the rear section supporting the typewriting machine 59; that the forward section 10 is provided with a novel guiding means comprising substantially parallel links 23 and 27, coupled to each other by the connecting link 29, by which guiding means said forward section may be sunk into the desk; that the rear section is guided on parallel links 32 and 33; and that there is provided a connecting link 39 between the two sets of guide-links, so that the typewriting machine is swung forwardly by the rear section 11 simultaneously with the sinking of the forward section 10 into the desk.

It will further be understood that the forward section 10 is provided with a panel 15 hinged at its under side and near the front edge of said section, to close the opening in the front wall of the desk into which opening the rear section 11 swings when the machine is brought forward; that this panel 15 serves as a means to prevent the accidental downward movement of the forward desk-top section 10; that there is pivoted a strip

12 between the forward and rear desk-top sections to prevent accidental forward movement of the rear desk-top section 11; and that said panel 15 and said strip 12 are connected to each other by the link 17, so that they may be rendered concomitantly ineffective prior to bringing the machine to its typing position.

It will also be understood that the intermediate strip 12 folds back on the forward desk-top section when it is rendered ineffective, and that the links 23 and 27 which guide the forward desk-top section are so constructed that the rear end of said forward section sinks deeper than its front end, so as to avoid interference of said strip with the rear desk-top section 11 when the latter is brought forward.

Variations may be resorted to within the scope of the invention, and portions of the improvements may be used without others.

Having thus described my invention, I claim:

1. The combination of a desk having a movable top, comprising a front table-section and a rear table-section normally in the same horizontal plane, a movable locking member separating said two sections normally in the same plane and secured to the front section, a bodily displaceable supporting member taking the downward thrust of the front table-section, means operatively connecting said supporting member to said locking member for concomitantly rendering both members ineffective by the operation of said locking member, and movable means connecting said sections for moving them.

2. The combination of a desk having a movable top, comprising a front table-section and a rear table-section normally in the same horizontal plane, a locking member separating said two sections normally in the same plane and secured to the front section, a bodily displaceable supporting member taking the downward thrust of the front table-section, means operatively connecting said supporting member to said locking member for concomitantly rendering both members ineffective by the operation of said locking member, and means for sinking said front table-section within the desk simultaneously with the forward advancement of the rear table-section.

3. In combination, a desk including side and rear panels, drawers, and an opening in the front of the frame of the desk, a sectional top including a front section and a rear section therefor horizontally movable to and in said opening and separated from the front section by an interposing comparatively narrow locking strip, movable means for moving said sections, a movable supporting strip in said opening and under the forward edge of the front section, said strips hinged to the front section, means connect-

ing the strips together for operating them concurrently, and a closure shelf normally beneath the rear section, and substantially in the same plane with said rear section when the latter is placed in typing position in said opening.

4. In combination, a desk including side and rear panels, drawers in the front of the desk, a sectional top including a front section and a rear section therefor and movable in a horizontal plane and separated from the front section by an interposing comparatively narrow locking strip, a movable supporting strip under the forward edge of the front section, a closure shelf normally beneath the rear section, and substantially in the same plane with said rear section when the latter is placed in typing position at the front of the desk, movable members operatively connecting said locking strip and said supporting strip, whereby both strips are simultaneously operated by the operation of said locking strip, means for rendering manually operable said locking strip, and movable supports for moving said front and rear sections, and maintaining them in a normal horizontally-aligning position with the front section and locking strip in horizontal planes substantially parallel with the shelf when the rear section is in said typing position, said supports being arranged laterally of said drawers and concealed by the side panels.

5. In combination, a desk including side and rear panels, drawers, an opening in the frame in the front of the desk, a sectional top including a front section and a rear section therefor movable in a horizontal plane forwardly to said opening and separated from the front section by an interposing comparatively narrow locking strip, a movable supporting strip in said opening under the forward edge of the front section, a closure shelf normally beneath the rear section, and substantially in the same plane with said rear section when the latter is placed in typing position, movable members operatively connecting said locking strip and said supporting strip to effectively operate both strips simultaneously by the operation of said locking strip, means for rendering manually operable said locking strip, and movable supports for said front and rear sections, maintaining them in a normal horizontally-aligning position with the locking strip, said supports being arranged laterally of said drawers and concealed by the side panels, said movable supports for the front section controlled by the travel of the rear section, and the operation of the locking strip displacing the supporting strip from said opening and permitting the front section to be forced downwardly within said opening and desk, previous to the advancing of the rear section to said opening and for

effectively preventing the front section from interfering with the operation of the rear section.

6. In a desk having a vertical opening in its front frame extending downwardly from the top of the desk, a flat top comprised of front and rear sections, the front sections sinkable within the desk and the rear section horizontally movable forward to the front of the desk, a locking strip between said sections, a supporting strip pivoted to the under side of the front section at its front edge and depending in said opening, means connecting said two strips for moving them into positions to support the front section and retain the sections horizontally aligned or out of said supporting and locking positions to permit the sections to be moved, whereby the movement of the locking strip from between the sections moves the supporting strip from said opening, vertically placed supporting links and levers, the levers having long and short arms, said links and levers pivoted at their lower ends to the desk-frame and at their upper ends to the rear section, and operable to move the rear section in a horizontal plane to the front of the desk and lower it in said opening, front and rear brackets fixed to the front section, front and rear T-shaped plates, the upper ends of the cross of said plates pivoted at different elevations to the desk-frame, links connecting the lower ends of the cross of the plates and the forward ends of the plates pivoted to said front and rear brackets, respectively, and vertical connecting links pivoted at their upper ends to said front plates and at their lower ends to the short arms of said levers.

7. In a desk, the combination of front and

40 rear sections and a middle strip normally lying between said sections, the three together normally forming a flat top for the desk, T-shaped links extended forwardly and rearwardly of the desk, the forward ends of their stems pivoted to the front section, and the upper ends of their bars pivoted to the desk-frame, links pivotally connecting the lower ends of said bars, vertical levers, their upper ends pivoted to the rear section and their lower ends to the desk-frame, vertical links, their upper ends pivoted to one of the T-shaped links and their lower ends to one of the levers, and hinges connecting the middle strip to the front section.

45 8. In a desk, the combination of front and rear sections and a middle strip normally lying between the sections and hinged to the front section, the three together normally constituting a flat top for the desk, a vertical panel, its upper edge hinged to the under side of the front section at its front edge and its lower edge resting upon the desk-frame, an arm extending forwardly from the middle strip, a link, its rear end pivoted to said arm and its front end to the lower edge of 50 the panel, T-shaped links extended forwardly and rearwardly of the desk, the forward ends of their stems pivoted to the front section and the upper ends of their bars pivoted to the desk-frame, links pivotally 55 connecting the lower ends of said bars, vertical levers, their upper ends pivoted to the rear section and their lower ends to the desk-frame, and vertical links, their upper ends pivoted to one of the T-shaped links 60 and their lower ends to one of the levers.

65 JOHN WALDHEIM.
